(57) **CLAIM**

The ornamental design for a model vehicle roof skid as shown and described.

DESCRIPTION

FIG. 1 is an upper, left, front perspective view of a model vehicle roof skid showing our new design;

FIG. 2 is an upper, right, rear perspective view thereof;

FIG. 3 is a lower, right, front perspective view thereof;

FIG. 4 is a lower, left, rear perspective view thereof;

FIG. 5 is a front elevation view thereof;

FIG. 6 is a rear elevation view thereof;

FIG. 7 is an upper plan view thereof;

FIG. 8 is a lower plan view thereof;

FIG. 9 is a right-side elevation view thereof; and,

FIG. 10 is a left-side elevation view of the model vehicle roof skid.

In the drawings, the broken lines illustrate portions of the model vehicle roof skid that form no part of the claimed design. Only the left-side model vehicle roof skid is shown. The right-side model vehicle roof skid is a mirror image of the shown model vehicle roof skid.
